CLAIM

(21) Appl. No.: **29/464,446**

The ornamental design for a collapsible candlestick and bud vase, as shown and described.

(22) Filed: **Aug. 16, 2013**

DESCRIPTION

(51) **LOC (10) Cl.** 26-01

FIG. 1 is a front view of a collapsible candlestick and bud vase according to the present design;

(52) **U.S. Cl.**

The rear and side views are identical to the front view thereof; FIG. 2 is a bottom view thereof;

USPC **D26/10**

FIG. 3 is a top view thereof;

(58) **Field of Classification Search**

FIG. 4 is a perspective view thereof;

USPC D26/5-23; D11/143-156, 131, 131.1, D11/157, 164; D6/556-558, 403-405; D8/1; 431/299, 125, 126, 292, 289; D7/500, 509, 523, 510, 511, 533, 532, D7/524, 566, 570, 545, 354, 586, 515, 518, D7/521, 549, 554.3, 562, 564; D9/428, D9/500, 502, 520, 538, 539; D19/88, D19/80-82, 84, 85; 220/8, 6; 215/382; 47/41.01; 383/104

FIG. 5 is a perspective view thereof with the design flipped such that the top portion and the bottom portion have been reversed so that the bottom portion appears at the top of the figure according to the present design;

See application file for complete search history.

FIG. 6 is a perspective view thereof with the top portion folded down according to the present design;

(56) **References Cited**

FIG. 7 is a perspective view thereof with the top portion folded down according to the present design and with the design flipped such that the top portion and the bottom portion have been reversed so that the bottom portion appears at the top of the figure according to the present design;

U.S. PATENT DOCUMENTS

FIG. 8 is a perspective view thereof with the top middle portion folded according to the present design;
